H. E. MALZARD

ADJUSTABLE COWL

Filed April 21, 1924

Inventor:

Herbert E. Malzard,

Witness:
Jas. L. Hutchinson:

Milano & Milano, Attorneys.

UNITED STATES PATENT OFFICE.

HERBERT E. MALZARD, OF PORTLAND, MAINE, ASSIGNOR TO THE THOMAS LAUGHLIN COMPANY, OF PORTLAND, MAINE, A CORPORATION OF MAINE.

ADJUSTABLE COWL.

Application filed April 21, 1924. Serial No. 708,049.

To all whom it may concern:

Be it known that I, HERBERT E. MALZARD, a citizen of the United States, residing at Portland, in the county of Cumberland and 5 State of Maine, have invented certain new and useful Improvements in Adjustable Cowls, of which the following is a specification, reference being had therein to the accompanying drawing.

10 This invention relates to improvements in adjustable cowls, and more especially to an improved adjustable ventilating cowl particularly adapted for vessels or ships.

The object of the invention is to provide 15 an improved adjustable cowl; to provide improved supporting and attaching means of a simple efficient nature providing for the adjustment of the cowl capable of being quickly and easily adjusted and that will 20 provide a firm, rigid connection and support.

The invention, with other objects and advantages thereof, and the particular construction, combination and arrangement of 25 parts comprising the same, will be understood from the following detailed description, when considered in connection with the accompanying drawings forming part hereof and illustrating one embodiment of 30 the invention.

In the drawing:

Figure 1 is a side elevation, with parts 35 shown in section, of an adjustable cowl constructed in accordance with the present invention.

Figure 2 is a detail perspective view of the supporting and attaching plate.

Fig. 3 is a detail perspective view of the clamping member.

40 Figs. 4 and 5 are detail views respectively of the cover plate and wrench for the same.

The invention comprehends a supporting and attaching member adapted to be secured to the deck of a vessel or the like, in 45 combination with a cowl adapted to seat on the supporting plate to be turned thereon, said supporting member having an opening therein and means thereon adapted to interfit with an end portion of the cowl to maintain the same in centered relation with the opening of the supporting plate, and means for clamping the cowl to the supporting and attaching member providing for rotary adjustment of the cowl including a flange on

the interior of the cowl, and a single clamping ring member adapted to be positioned 55 interiorly of the cowl, said clamping ring member having an outstanding flange to fit over the flange of the cowl and having a rotatable adjustable connection with the supporting member.

While a specific embodiment of the invention is illustrated in the drawings, it will of course be understood that minor changes and variations in the particular construction shown, and the embodiment of the invention in other forms, as will appeal to those skilled in the art and falling within the scope of the appended claims, may be practiced without departing from the spirit 70 of the invention.

Referring to a detail description of the particular embodiment of the invention illustrated in the drawings, the supporting and attaching member is shown as a plate 75 1 having a circular opening 2, and an adjoining tubular part 3, said plate being adapted to be secured by screws 4 or equivalent means to the deck 5 of a vessel or the like, as illustrated Figure 1 of the drawings, 80 at a ventilating opening therein with the tubular part 3 of the supporting member fitting within the opening.

6 designates the cowl comprising a lower cylindrical part 6^a and an enlarged upper 85 part 6^b having a mouth 6^c disposed at substantially right angles to the longitudinal axis of the lower part 6^a, the cowl being adapted to seat at its lower end upon the supporting and attaching member with its 90 lower part 6^a in alignment with the ventilating opening of the deck, and to be rotated or turned on the supporting and attaching plate 1 to adjust the same with its mouth 6^c facing in different directions as 95 desired.

The means for adjustably securing the cowl 6 upon the supporting plate 1 comprises an annular flange 6^d on the interior of the lower part 6^a of the cowl, and a ring member 7 having a rotary adjustable connection with the supporting plate 1 and provided with an outstanding portion or flange 7^a adapted to fit over the flange 6^d of the cowl 6, said ring member 7 being adapted to securely clamp the lower end of the cowl 6 to the supporting plate 1. The rotary adjustable connection between the ring member 7

and the supporting and attaching plate 1 is formed by an interiorly threaded portion 3^a on the tubular part 3 of the supporting and attaching plate and an exteriorly threaded portion 7^b on the ring member 7, the ring member 7 being adapted to be arranged interiorly of the cowl and the tubular part 3. 8 designates a radially extending bar on the ring member 7 rigid therewith for operating 10 the same, the clamping ring member 7 being operable either from above the deck or from within the cabin. As will be understood to adjust the cowl the clamping ring member 7 is unscrewed sufficiently to release the cowl 15 6, which is turned to point its mouth in the desired direction, and the clamping ring member 7 is then turned up to lock the cowl in adjustable position.

Means is provided for maintaining the 20 lower end of the cowl 6 on the supporting plate 1 in proper centered relation with the opening 2 thereof. The means for this purpose in the particular exemplification of the invention shown in the drawing, comprises 25 an annular depression or recess 1^a in the plate 1, surrounding the opening 2 of the plate, and a depending annular portion 9 on the flange 6^a of the cowl 6 adapted to fit within the depression or recess 1^a of the supporting and attaching plate 1, an interfitting connection being thus afforded, which also functions in conjunction with the clamping means to provide a rigid connection and support for the cowl.

35 10 designates a cover plate adapted to be employed to close the ventilating opening in the deck when the cowl is not in use, said cover plate being adapted to fit within the annular depression or recess 1^a of the supporting and attaching plate 1 and having an exteriorly threaded depending portion 10^a adapted to engage the interiorly threaded portion 3^a of the tubular extension 3 of the supporting and attaching plate. The cover plate 10 is shown provided with recesses 10^b for engagement by a tool 11 for turning the same.

It will be noted that by the special construction and arrangement of parts hereinbefore described a very efficient adjustable cowl device is provided. The supporting and attaching means is of a simple nature that will afford a firm rigid support and connection for the cowl and is capable of 55 being quickly and easily adjusted. Only a single clamping member is required and the clamping means is arranged interiorly of the cowl and adapted to be readily adjustable either from the deck of the vessel or from within the cabin.

60 What I claim is:

1. In a device of the class described, a supporting plate having an opening, a cowl adapted to seat and be turned upon the supporting plate, means on the supporting plate

for engaging an end portion of the cowl to hold the cowl in centered relation with the opening of the supporting plate, and means for clamping the cowl to the supporting plate providing for rotary adjustment of the cowl, said means including a laterally extending flange on the interior of the cowl, a ring member adapted to be arranged interiorly of the cowl, and having an outstanding portion to fit over the interior flange of the cowl, means on the ring member and the supporting plate providing a rotary adjustable connection between the ring member and the supporting plate, and means on the ring member for turning the same. 80

2. In a device of the class described, a supporting member comprising a plate provided with a circular opening, and having an annular depression surrounding the opening, and a tubular extension adjoining the opening, a cowl having a lower end portion adapted to seat within the depression of the supporting member, and means for clamping the cowl to the supporting member providing for rotary adjustment of the cowl, 85 said means including a laterally extending flange on the interior of the cowl, a ring member adapted to be arranged interiorly of the cowl, and having an outstanding portion to fit over the interior flange of the cowl, means on the ring member and the tubular extension providing a rotary adjustable connection therebetween, and means on the ring member for turning the same. 90

3. In a device of the class described, a supporting member including a tubular part, a cowl adapted to seat upon the supporting member, and means for clamping the cowl to the supporting member providing for rotary adjustment of the cowl, said means including a laterally extending flange on the interior of the cowl, a ring member adapted to be arranged interiorly of the cowl and said tubular part, and having an outstanding portion to fit over the interior flange of the cowl, means on the ring member and the interior of the tubular part providing a rotary adjustable connection between the ring member and the supporting member, and means on the ring member for turning the same. 100 105 110

4. In a device of the class described, a supporting member including a tubular part, a cowl adapted to seat upon the supporting member, and means for clamping the cowl to the supporting member providing for rotary adjustment of the cowl, said means including a laterally extending flange on the interior of the cowl, a ring member adapted to be arranged interiorly of the cowl and said tubular part, and having an outstanding portion to fit over the interior flange of the cowl, means on the ring member and the interior of the tubular part providing a rotary adjustable connection between the ring member and the supporting member, and means on the ring member for turning the same. 120 125 130

member and the supporting member, and said ring member having a transverse bar for turning the same.

5. In a device of the class described, a supporting port comprising a plate having a circular opening, and having an annular recess adjacent the opening, and a tubular extension adjoining the opening, a cowl provided with an inwardly extending annular flange on 10 the lower end thereof, said flange having a depending portion, the lower end of the cowl being adapted to seat upon the supporting member with the depending portion of said flange fitting within the annular recess 15 of the supporting member, a ring member arranged interiorly of the cowl and said tubular part and provided with an outstanding annular flange to fit over the said flange of the cowl, and an adjustable threaded connection between the ring member and said tubular part, and means on the ring member 20 for turning the same, said ring member being adapted to be adjusted to clamp the cowl to the supporting member.
- 25 6. In a device of the class described, a supporting member comprising a plate having a circular opening, and having an annular recess surrounding the opening, and a tubular extension adjoining the opening, a cowl provided with an inwardly extending annular flange on the lower end thereof, said flange having a depending portion, the lower 30 end of the cowl being adapted to seat upon the supporting member with the depending portion of said flange fitting within the an-
- nular recess of the supporting member, a ring member arranged interiorly of the cowl and said tubular part and provided with an outstanding annular flange to fit over the said flange of the cowl, said tubular part 40 having an interiorly threaded portion, and said ring member having an exteriorly threaded portion to adjustably engage the threaded portion of the tubular part, means on the ring member for turning the same, 45 said ring member being adapted to be adjusted to clamp the cowl to the supporting member, the upper portion of the threaded tubular part being formed and adapted, upon removal of the cowl and ring member 50 to receive a corresponding threaded cover plate to close the opening.
7. In a device of the class described, a supporting plate having an opening, a pipe adapted to seat upon the supporting plate, 55 and means for clamping said pipe to the supporting plate providing for rotary adjustment of the pipe, said means including a flange on the pipe extending inwardly thereof, a ring member adapted to be arranged 60 interiorly of the pipe, and having an outstanding portion to fit over the flange of the pipe, means on the ring member and the supporting plate providing a rotary adjustable connection between the ring member 65 and the supporting plate, and means on the ring member for turning the same.

In testimony whereof I hereunto affix my signature.

HERBERT E. MALZARD.
